UNITED STATES PATENT OFFICE.

EPHRAIM WILLIAM HAVERS, OF LONDON, ENGLAND.

APPARATUS FOR DISTANCE GAS-LIGHTING.

1,132,933.

Specification of Letters Patent. Patented Mar. 23, 1915.

Application filed December 12, 1913. Serial No. 806,160.

To all whom it may concern:

Be it known that I, EPHRAIM WILLIAM HAVERS, a subject of the King of Great Britain, residing at London, England, have 5 invented new and useful Improvements in Apparatus for Distance Gas-Lighting, of which the following is a specification.

My invention relates to improvements in apparatus for distance control and ignition 10 of gas burners of that kind which consist of a valve for controlling the supply of gas combined with a burner in which is arranged an electrical igniting device.

The object of my present invention is to 15 provide an apparatus which is simpler in construction than heretofore, is easily accessible for cleaning, and which is self-contained. Furthermore, the apparatus hereinafter described is suitable not only for 20 coal-gas burners, but for burners for petrol-air-gas, and other like mixtures.

In the accompanying drawings Figure 1 illustrates in partial vertical section one form of apparatus constructed according to 25 my present invention and applied to an inverted burner; Fig. 2 an underside view of the lower end of Fig. 1; Fig. 3 an enlarged view of the electrical igniter of Fig. 1; Figs. 4 and 5 detail views of modified forms 30 of burner ends; Fig. 6 a section of a modified form of regulator; Figs. 7 to 10 illustrate various modified forms of inverted burners; and Fig. 11 shows the application of my invention to an upright burner.

Similar letters of reference relate to like parts in all the figures of the drawings.

Referring to Figs. 1, 2 and 3, *g* is the casing containing any suitable valve device for controlling the admission of gas, and 40 below the connection *c* is situated a regulator or nipple consisting of an inner part *n* having a plurality of holes, and in the case of a regulator as shown, each hole is furnished with a tapered needle *p* or the like 45 arranged to enter or recede from its hole, thus regulating the opening of the same. The needles *p* are carried by a small cup *q* which is raised and lowered by means of a crank-pin *r* acting upon a slot in the cup *q* when the button *s* is turned in either direction. Or I sometimes employ a regulator of the kind shown in Fig. 6, in which the regulating screw *t* is adapted to shut off one or more of the holes *u* as the said

screw *t* is turned more or less in one direction.

The outer part *o* of the regulator or nipple (Fig. 1) is electrically insulated from the inner part *n*, and to the latter part is attached a central conductor-rod *v* which 60 extends in a downward direction as shown in Fig. 1 (or in an upward direction in the case of an upright burner to be hereinafter described with reference to Fig. 11), and is connected at the lower end to the central 65 tube *w* of the igniter device by sliding therein or thereon, or otherwise. The central tube *w* of the igniter is diverted from the central line as shown in Figs. 1 and 3, and passes through an insulating block *x* contained within the outer metal tube *y*, and receives one end of the platinum igniting coil or filament *z*, the other end of the latter being similarly held in a short metal tube 70 2 which is partly embedded in the insulating 75 block *x* but is in electrical contact with the outer metal tube *y*. The ends of the coil or filament *z* are retained in their respective tubes *w* and 2 by any suitable means, as for example by crushing the ends of the said 80 tubes around the ends of the coil or filament in a known manner. The upper end of the outer metal tube *y* of the igniter is connected to the lower end of the ordinary 85 mixing tube or chamber 3 by means of a conical connection 4 with air openings 5 in the side wall thereof in which may be fitted a gauze, and the whole may be inclosed by a screwed nozzle 6. Or the conical connection 4 may be perforated in such a manner 90 as to allow the gauze to be dispensed with. The annular space 7 between the inner circumference of the nozzle 6 and the outer circumference of the igniter tube *y* form 95 the aperture through which the gas and air mixture issues, and is ignited by the incandescent coil or filament *z* in the igniter tube *y*. The nozzle 6 may have prongs or radial ribs 18 internally for centering the igniter and insuring its correct position.

On gas being admitted to the regulator or nipple *o* through the valve, it passes with an appropriate quantity of air down the mixing tube or chamber 3 to the nozzle 6 where it issues by the annular aperture 7 100 105 and is ignited by the incandescent coil or filament *z* within the igniter tube *y*. The coil or filament *z* is rendered incandescent

by a current of electricity which may pass from the terminal *i* of the valve-actuating device, through the central insulated metal portion *n* to the regulator or nipple, and 5 thence by the central conductor rod *v* to the central tube *w* of the igniter, and through the coil or filament *z* rendering the same incandescent. The current leaves the other end of the coil or filament *z* by the short 10 length of tube 2 and passes through the outer metal tube *y*, the conical connector 4, the mixing tube or chamber 3, the outer part *o* of the regulator or nipple, to the terminal *j*. Or the connections may be varied 15 according to requirements.

When employing an inverted burner for petrol-air-gas or other like mixtures, I prefer to employ a nozzle fitted with gauze or perforations at the orifice thereof surrounding 20 the ignition chamber, for the purpose of breaking up the mixture and assisting ignition. Fig. 4 shows a number of slots or perforations *b* formed in a metal cap *d* screwed on to the end of the burner nozzle 25 6; and Fig. 5 shows an annular gauze ring *e* held in place on the nozzle burner 6 by means of a cap *f* screwed on to the said nozzle. Or the slots or perforations *b* may be formed in the end of the nozzle 6 itself. 30 In the modification illustrated in Figs. 7 and 8 the upper ends of the conductors 8, 9 are connected below the gas regulator or nipple *o* to two separate upwardly extending semi-cylindrical members 19, 20 and 35 mounted on a common insulating base 22 (which may also form a choke-bore as shown) and be adapted to fix on to similar electrical conductors 8^x, 9^x above by a bayonet joint thereby completing electric connection 40 to the igniter and forming a support for the burner in a simple and efficient manner. Or the conductors may extend through holes drilled on either side of the gas regulator, always being suitably insulated 45 therefrom.

Chokebores for securing efficient mixing may be fitted as desired, and in some cases these choke-bores may have grooves or slots to allow the passage of the conductors 8, 9 50 instead of these passages being formed in the mixing tube 3. Or the mixing tube may be rifled, and the conductors 8, 9 bent to lie in the recesses outside the said mixing tube.

55 In the modification illustrated in Fig. 9 the mixing tube 3 and the burner nozzle 6 (to avoid direct conduction of heat) are connected to flanged extensions 23 and 24. Layers of insulating material 27 and 28, 60 such as asbestos for example, are provided between these flanged extensions 23 and 24, and the whole are clamped together by any convenient means which maintain the insulation of the said parts 23 and 24. In 65 this case the conductors 8, 9 may be entirely

external, and be formed of depending members as shown, the current from these being led into the nozzle 6 through the screws 25 and 26 as shown. A similar arrangement is illustrated in Fig. 10 applied to a burner 70 with a central conductor rod *v*, the electrical connection between the conductor 9 and the outer metal tube *y* of the igniter being effected through the screw 25, flange 24, and cone 4; and between the conductor 8 and 75 the central rod *v* through the screw 26 and the horizontal extension *v*^x of the said rod.

Fig. 11 illustrates the application of the central conductor rod *v* (hereinbefore described with reference to Fig. 1), to an upright form of burner, in which it will be seen that the igniter tube *y* is disposed centrally of the burner proper 29, and that the valve casing *g* and its actuating parts are arranged at the lower part of the burner fitting. In other respects the construction of this upright burner is on the same lines as already described in connection with the inverted burners.

Claims:

1. Apparatus for distance control and ignition of gas, comprising a burner nozzle 6, an electrically incandescent filament (*z*) mounted in two tubes (*w*, 2) insulated from one another and contained within a short 90 metal tube (*y*) disposed centrally of the interior of the said nozzle (6), a gas regulator (*o*) with an insulated central portion (*n*), a central conductor rod (*v*) between the said insulated central portion (*n*) of 95 the regulator (*o*) and the tube (*w*) carrying one end of the filament (*z*), the tube (2) which carries the other end of the said filament being in contact with the before mentioned short metal outer tube (*y*) and 100 outer casing of the apparatus, substantially as described.

2. Apparatus for distance control and ignition of gas, comprising a burner nozzle (6), an electrically incandescent filament (*z*) mounted in two tubes (*w*, 2) insulated from one another and contained within a short metal tube (*y*) disposed centrally of the said nozzle (6), a gas regulator (*o*), an insulating base (22), two separate semi-cylindrical members (19, 20) mounted upon the said base (22) which complete the electric circuit to the filament (*z*) and form a support for the burner, substantially as described.

3. Apparatus for distance control and ignition of gas, comprising a burner nozzle (6), an electrically incandescent filament (*z*) mounted in two tubes (*w*, 2) insulated from one another and contained within a short metal tube (*y*) disposed centrally of the interior of the said nozzle (6), a gas regulator (*o*) with a plurality of holes and formed of two separate insulated parts (*o*, *n*), and a central conductor rod (*v*) 120 125 130

removably and centrally connected to the inner separate insulated part (n) of the said regulator (o), substantially as described.

4. Apparatus for distance control and ignition of gas, comprising a burner nozzle (6), an electrically incandescent filament (z), an insulating block (x), a short tube (w) in the said block (x) which receives one end of the said filament (z), and an other short tube (2) in metallic connection

with the casing (y) containing the said insulating block (x), substantially as described.

In testimony whereof I have signed my name to this specification in the presence of 15 two subscribing witnesses.

EPHRAIM WILLIAM HAVERS.
